(57) **ABSTRACT**

The present invention relates to bisarylimidazolyl derivatives and pharmaceutical compositions comprising said compounds inhibiting fatty acid amide hydrolase and useful for the treatment of pain, particularly neuropathic pain, psychomotor disorder, hypertension, cardiovascular disease, eating disorder, nausea, AIDS-related complex, glaucoma, inflammation, psoriasis or multiple sclerosis, and other conditions the treatment of which can be effected by inhibiting fatty acid amide hydrolase.

FIG 3.

BISARYLIMIDAZOLY FATTY ACID AMIDE HYDROLASE INHIBITORS

Matter enclosed in heavy brackets [ ] appears in the original patent but forms no part of this reissue specification; matter printed in italics indicates the additions made by reissue.

[CROSS REFERENCE TO RELATED APPLICATION]

This non-provisional application claims priority from provisional application U.S. Ser. No. 60/286,827 filed Apr. 27, 2001.]

CROSS REFERENCE TO RELATED APPLICATIONS

This application is a reissue application of U.S. Pat. No. 6,562,846, issued May 13, 2003, on non-provisional application No. 10/128,480, filed Apr. 23, 2002 which claims priority from provisional application USSN 60/286,827 filed Apr. 27, 2001.

FIELD OF THE INVENTION

The present invention relates to bisarylimidazolyl derivatives and pharmaceutical compositions comprising said derivatives which inhibit fatty acid amide hydrolase and are useful for the treatment of conditions affected by inhibiting fatty acid amide hydrolase.

BACKGROUND

Neuropathic pain is caused by injury to nerves as the result of many factors including physical damage (e.g., trauma, surgery), drugs such as Zidovudine (AZT), Carmustine (BCNU) and disease (e.g., diabetes, herpes zoster). The prevalence in the United States of neuropathies associated with diabetes, herpes and amputation is estimated at 1.5 million. The worldwide prevalence of diabetic neuropathy alone is expected to reach 12 million by 2007. Nerve injury can result in both allodynia and hyperalgesia.

Current treatment of neuropathic pain involves the use of non-steroidal anti-inflammatory drugs (NSAIDs) such as aspirin and acetaminophen) and other analgesics as well as anticonvulsants (e.g., carbamazepine, gabapentin) and tricyclic antidepressants (e.g., amitriptyline). Effective treatment of pain with current therapies is limited by adverse effects and a lack of efficacy against all components of pain.

Current research is aimed at understanding the molecular and physiological components of pain processing to develop more effective analgesics (Levin, J. D., New Directions in Pain Research: Meeting Report Molecules to Maladies, *Neuron* 20: 649-654, 1998; Pasternak, G. W., The Central Questions in Pain Perception May Be Peripheral, *PNAS* 95:10354-10355, 1998).

The analgesic properties of cannabinoids have been known for many years and to many cultures. Cannabinoids are active in many pre-clinical models of pain, including neuropathic pain. Within the last few years, several endogenous cannabinoids, including the fatty acid amides arachidonyl ethanolamide (anandamide), and arachidonyl amino acids such as N-arachidonylglycine, homo- γ -linolenyl-ethanolamide and docosatetraenyl-ethanolamide, as well as 2-arachidonyl-glycerol, have been shown to induce analgesia in laboratory animals (De Vane, W.A. et. al., Isolation and Structure of a Brain Constituent That Binds to the Cannabinoid Receptors, *Science* 258: 1946-1949, 1992;

Hanus, L. et. al., Two New Unsaturated Fatty Acid Ethanolamides in Brain that Bind to the Cannabinoid Receptor, *J. Med. Chem.* 36: 3032-3034, 1993; Machoulam, R. et. al., Identification of an Endogenous 2-Monoglyceride, Present in Canine Gut, That Binds To Cannabinoid Receptors, *Biochem. Pharmacol.* 50: 83-90, 1995; Vogel, Z. et. al., Cannabinomimetic Behavioral Effects of and Adenylate Cyclase Inhibition By Two New Endogenous Anandamides, *Eur. J. Pharmacol.* 287: 145-152, 1995; Hargreaves, K. M. et. al., Cannabinoids Reduce Hyperalgesia and Inflammation Via Interaction With Peripheral CB1 Receptors, *Pain* 75: 111-119, 1998; Rice, A. S. C., et. al., The Anti-Hyperalgesic Actions of the Cannabinoid Anandamide and the Putative CB2 Receptor Agonist Palmitoylethanolamide in Visceral and Somatic Inflammatory Pain, *Pain* 76: 189-199, 1998; Huang, S. M., et. al., Identification of a New Class of Molecules, the Arachidonyl Amino Acids, and Characterization of One Member That Inhibits Pain, *J. Biological Chemistry*, 276: 46, 42639-42644, 2001). The ability of cannabinoid receptor antagonists and cannabinoid receptor antisense to induce hyperalgesia in animals suggests that endogenous cannabinoids regulate the nociceptive threshold (Hargreaves, K. M. et. al., Hypoactivity of the Spinal Cannabinoid System Results in NMDA-Dependent Hyperalgesia, *J. Neurosci.* 18: 451-457, 1998; Piomelli, D. et. al., Control of Pain Initiation By Endogenous Cannabinoids, *Nature* 394: 277-281, 1998; Fields, H. L. et. al., An Analgesia Circuit Activated By Cannabinoids, *Nature* 395: 381-383, 1998). Elevation of levels of neuroactive fatty acid amides such as anandamide may provide a unique mechanism to achieve analgesia. The mechanisms by which endogenous cannabinoids are synthesized are not well understood; therefore, target for drugs aimed at increasing the synthesis of these compounds are slow to be identified.

Anandamide and the other identified endogenous cannabinoids are inactivated through a cleavage mechanism by a membrane-bound enzyme, fatty acid amide hydrolase (FAAH). FAAH, therefore, provides an important target for regulating the activity of endogenous cannabinoids. The inhibition of FAAH may elevate levels of anandamide or other endogenous cannabinoids to increase the nociceptive threshold. Furthermore, the inhibition of FAAH would also extend the therapeutic benefits of other cannabinoid agonists in the treatment of emesis, anxiety, feeding, behaviors, movement disorders, glaucoma, neuroprotection and cardiovascular disease.

SUMMARY OF THE INVENTION

Thus according to a first embodiment of the first aspect of the present invention are provided compounds of Formula (I)

and pharmaceutically acceptable salts and solvates thereof wherein

R^1 and R^2 are each independently H, C_{1-3} alkyl or halo;
 R^3 is C_1-C_3 alkyl or C_{3-7} cycloalkyl;

A is C_{1-12} alkylene or L;

L is $-phenyl-O-C_{1-4}$ alkylene wherein said C_{1-4} alkylene is attached to D; provided that if A is L, then D is $X(O)O$ and A—D is not interrupted with $J-J'$, $-Z-phenyl-$ or $-Z-C_{1-3}$ alkylene;

D is $X(O)O$, $X(O)N(G')$, $HYC(O)O$ or $HYC(O)ON=C(G')$;

X is C and is attached to A;

Y is N and is attached to A;

G is H, C_{1-5} alkyl, C_{1-5} haloalkyl, C_{3-7} cycloalkyl, phenyl, $-C_{1-2}$ alkylene-phenyl, C-pyridyl or N-pyridyl, said phenyl or $-C_{1-2}$ alkylene-phenyl are each optionally and independently substituted with one or more of the same or different substituents selected from the group consisting of halo, NO_2 , CN, $-C(O)O-C_{1-3}$ alkyl, C_{1-3} alkyl, hydroxy and C_{1-3} alkoxy;

G' is H, C_{1-5} alkyl or C_{1-5} haloalkyl;

wherein A—D is optionally interrupted with $J-J'$, $-Z-phenyl-$ or $-Z-C_{1-3}$ alkylene;

wherein

Z is O or S and is attached to A;

J is CH and is attached to A, D and J' ;

J' is C_{1-4} alkyl or phenyl; and

provided that

if A—D is interrupted with $-Z-phenyl-$, then A is C_{1-5} alkylene;

if A—D is not interrupted with $-Z-phenyl-$, then A is C_{5-12} alkylene.

According to another embodiment of the first aspect of the present invention are provided compounds of Formula (I) according to the first embodiment of the first aspect wherein R^1 and R^2 are each H.

According to another embodiment of the first aspect of the present invention are provided compounds of Formula (I) according to the first embodiment of the first aspect wherein R^1 and R^2 are each halo.

According to another embodiment of the first aspect of the present invention are provided compounds of Formula (I) according to the first embodiment of the first aspect wherein R^1 and R^2 are each fluoro.

According to another embodiment of the first aspect of the present invention are provided compounds of Formula (I) according to the first embodiment of the first aspect wherein R^3 is methyl.

According to another embodiment of the first aspect of the present invention are provided compounds of Formula (I) according to the first embodiment of the first aspect wherein R^3 is ethyl.

According to another embodiment of the first aspect of the present invention are provided compounds of Formula (I) according to the first embodiment of the first aspect wherein A is L.

According to another embodiment of the first aspect of the present invention are provided compounds of Formula (I) according to the first embodiment of the first aspect wherein A is C_{3-10} alkylene.

According to another embodiment of the first aspect of the present invention are provided compounds of Formula (I) according to the first embodiment of the first aspect wherein A is C_{7-10} alkylene.

According to another embodiment of the first aspect of the present invention are provided compounds of Formula (I) according to the first embodiment of the first aspect wherein A is C_{4-8} alkylene.

According to another embodiment of the first aspect of the present invention are provided compounds of Formula (I) according to the first embodiment of the first aspect wherein A is C_{5-7} alkylene.

According to another embodiment of the first aspect of the present invention are provided compounds of Formula (I) according to the first embodiment of the first aspect wherein A is C_{8-9} alkylene.

According to another embodiment of the first aspect of the present invention are provided compounds of Formula (I) according to the first embodiment of the first aspect wherein A is C_{9-10} alkylene.

According to another embodiment of the first aspect of the present invention are provided compounds of Formula (I) according to the first embodiment of the first aspect wherein A is C_{6-7} alkylene.

According to another embodiment of the first aspect of the present invention are provided compounds of Formula (I) according to the first embodiment of the first aspect wherein A is C_{1-4} alkylene.

According to another embodiment of the first aspect of the present invention are provided compounds of Formula (I) according to the first embodiment of the first aspect wherein D is $X(O)O$.

According to another embodiment of the first aspect of the present invention are provided compounds of Formula (I) according to the first embodiment of the first aspect wherein D is $X(O)N(G')$.

According to another embodiment of the first aspect of the present invention are provided compounds of Formula (I) according to the first embodiment of the first aspect wherein D is $HYC(O)O$.

According to another embodiment of the first aspect of the present invention are provided compounds of Formula (I) according to the first embodiment of the first aspect wherein D is $HYC(O)ON=C(G')$.

According to another embodiment of the first aspect of the present invention are provided compounds of Formula (I) according to the first embodiment of the first aspect wherein G is C_{1-5} alkyl.

According to another embodiment of the first aspect of the present invention are provided compounds of Formula (I) according to the first embodiment of the first aspect wherein G is C_{3-7} cycloalkyl.

According to another embodiment of the first aspect of the present invention are provided compounds of Formula (I) according to the first embodiment of the first aspect wherein G is $-C_{1-2}$ alkylene-phenyl, said phenyl or phenyl of said $-C_{1-2}$ alkylene-phenyl are optionally substituted with the same or different substituents selected from the group consisting of halo, CN, $-C(O)O-C_{1-3}$ alkyl, C_{1-3} alkyl and C_{1-3} alkoxy.

According to another embodiment of the first aspect of the present invention are provided compounds of Formula (I) according to the first embodiment of the first aspect wherein G is phenyl or $-C_{1-2}$ alkylene-phenyl, said phenyl or phenyl of said $-C_{1-2}$ alkylene-phenyl are substituted with halo, $-C(O)O-C_{1-3}$ alkyl, C_{1-3} alkyl or C_{1-3} alkoxy.

According to another embodiment of the first aspect of the present invention are provided compounds of Formula (I) according to the first embodiment of the first aspect wherein G is phenyl or $-C_{1-2}$ alkylene-phenyl, said phenyl or phenyl of said $-C_{1-2}$ alkylene-phenyl are substituted with fluoro.

According to another embodiment of the first aspect of the present invention are provided compounds of Formula (I) according to the first embodiment of the first aspect wherein G is phenyl or $-C_{1-2}\text{alkylene-phenyl}$, said phenyl or phenyl of said $-C_{1-2}\text{alkylene-phenyl}$ are substituted with cyano.

According to another embodiment of the first aspect of the present invention are provided compounds of Formula (I) according to the first embodiment of the first aspect wherein A—D are not interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein A—D are interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein A—D is interrupted with J—J'.

According to another embodiment of the first aspect of the present invention are provided compounds of Formula (I) according to the first embodiment of the first aspect wherein A—D is interrupted with —Z—phenyl-.

According to another embodiment of the first aspect of the present invention are provided compounds of Formula (I) according to the first embodiment of the first aspect wherein A—D is interrupted with —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{7-10}\text{alkylene}$, D is X(O)O and A—D is not interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{1-5}\text{alkylene}$, D is X(O)O and A—D is interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{7-10}\text{alkylene}$, D is X(O)N(G') and A—D is not interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{1-5}\text{alkylene}$, D is X(O)N(G') and A—D is interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{7-10}\text{alkylene}$, D is HYC(O)O and A—D is not interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{1-5}\text{alkylene}$, D is HYC(O)O and A—D is interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{7-10}\text{alkylene}$, D is HYC(O)ON=G' and A—D is not interrupted with J—J', —Z—phenyl- or —Z— $C_{1-3}\text{alkylene}$.

is HYC(O)ON=G' and A—D is not interrupted with J—J', —Z—phenyl- or —Z— $C_{1-3}\text{alkylene}$.

According to another embodiment of the first aspect of the present invention are provided compounds of Formula (I) according to the first embodiment of the first aspect wherein R¹ and R² are each H, R³ is $C_{1-3}\text{alkyl}$, A is $C_{1-5}\text{alkylene}$, D is HYC(O)ON=G' and A—D is interrupted with J—J', —Z—phenyl- or —Z— $C_{1-3}\text{alkylene}$.

According to another embodiment of the first aspect of the present invention are provided

10 [6-(2-Methyl-4,5-diphenyl-imidazol-1-yl)-hexyl]-carbamic acid 2-fluoro-phenyl ester;

[6-(2-Ethyl-4,5-diphenyl-imidazol-1-yl)-hexyl]-carbamic acid tert-butyl ester;

15 [6-(2-Ethyl-4,5-diphenyl-imidazol-1-yl)-hexyl]-carbamic acid sec-butyl ester;

[6-(2-Methyl-4,5-diphenyl-imidazol-1-yl)-hexyl]-carbamic acid benzyl ester;

 {4-[3-(2-Methyl-4,5-diphenyl-imidazol-1-yl)-propoxy]-phenyl}-carbamic acid 2,6-difluoro-phenyl ester;
 {4-[2-(2-Methyl-4,5-diphenyl-imidazol-1-yl)-ethoxy]-phenyl}-carbamic acid ethyl ester;
 [1-Methyl-6-(2-methyl-4,5-diphenyl-imidazol-1-yl)-hexyl]-carbamic acid 2-fluoro-phenyl ester;
 [1-Ethyl-6-(2-methyl-4,5-diphenyl-imidazol-1-yl)-hexyl]-carbamic acid 2-fluoro-phenyl ester;
 [1-Isopropyl-6-(2-methyl-4,5-diphenyl-imidazol-1-yl)-hexyl]-carbamic acid 2-fluoro-phenyl ester or
 [6-(2-Methyl-4,5-diphenyl-imidazol-1-yl)-1-phenyl-hexyl]-carbamic acid 2-fluoro-phenyl ester.
 According to another embodiment of the first aspect of the present invention are provided
 [6-(2-Methyl-4,5-diphenyl-imidazol-1-yl)-hexyl]-carbamic acid 2-fluoro-phenyl ester;
 [2-Propanone,O-[6-(2-methyl-4,5-diphenyl-1H-imidazol-1-yl)hexyl]amino]carbonyl]oxime;
 2-Propanone,O-[6-(2-methyl-4,5-diphenyl-1H-imidazol-1-yl)hexylaminocarbonyl]oxime;
 [6-(2-Methyl-4,5-diphenyl-imidazol-1-yl)-hexyl]-carbamic acid cyclohexyl ester;
 [6-(2-Methyl-4,5-diphenyl-imidazol-1-yl)-hexyl]-carbamic acid methyl ester;
 [6-(2-Methyl-4,5-diphenyl-imidazol-1-yl)-hexyl]-carbamic acid phenyl ester;
 [6-(2-Methyl-4,5-diphenyl-imidazol-1-yl)-hexyl]-carbamic acid phenyl ester;
 [6-(2-Methyl-4,5-diphenyl-imidazol-1-yl)-hexyl]-carbamic acid 2,4-difluoro-phenyl ester;
 [6-(2-Methyl-4,5-diphenyl-imidazol-1-yl)-hexyl]-carbamic acid 4-chloro-phenyl ester;
 [6-(2-Methyl-4,5-diphenyl-imidazol-1-yl)-hexyl]-carbamic acid 4-methoxy-phenyl ester;
 [6-(2-Methyl-4,5-diphenyl-imidazol-1-yl)-hexyl]-carbamic acid o-tolyl ester;
 [6-(2-Methyl-4,5-diphenyl-imidazol-1-yl)-hexyl]-carbamic acid 4-cyano-phenyl ester;
 [6-(2-Methyl-4,5-diphenyl-imidazol-1-yl)-hexyl]-carbamic acid 2,6-dimethoxy-phenyl ester;
 [6-(2-Methyl-4,5-diphenyl-imidazol-1-yl)-hexyl]-carbamic acid 2-methoxy-phenyl ester;
 [7-(2-Methyl-4,5-diphenyl-imidazol-1-yl)-heptyl]-carbamic acid methyl ester;
 [7-(2-Methyl-4,5-diphenyl-imidazol-1-yl)-heptyl]-carbamic acid ethyl ester;
 [7-(2-Methyl-4,5-diphenyl-imidazol-1-yl)-heptyl]-carbamic acid phenyl ester;
 [7-(2-Methyl-4,5-diphenyl-imidazol-1-yl)-heptyl]-carbamic acid 4-fluoro-phenyl ester;
 [7-(2-Methyl-4,5-diphenyl-imidazol-1-yl)-heptyl]-carbamic acid 2-fluoro-phenyl ester;

[7-(2-Methyl-4,5-diphenyl-imidazol-1-yl)-heptyl]-carbamic acid 2,4-difluoro-phenyl ester;
 [7-(2-Methyl-4,5-diphenyl-imidazol-1-yl)-heptyl]-carbamic acid 4-chloro-phenyl ester;
 [7-(2-Methyl-4,5-diphenyl-imidazol-1-yl)-heptyl]-carbamic acid 4-methoxy-phenyl ester;
 [7-(2-Methyl-4,5-diphenyl-imidazol-1-yl)-heptyl]-carbamic acid o-tolyl ester;
 [7-(2-Methyl-4,5-diphenyl-imidazol-1-yl)-heptyl]-carbamic acid 4-cyano-phenyl ester;
 [7-(2-Methyl-4,5-diphenyl-imidazol-1-yl)-heptyl]-carbamic acid 2,6-dimethoxy-phenyl ester;
 [7-(2-Methyl-4,5-diphenyl-imidazol-1-yl)-heptyl]-carbamic acid 2-methoxy-phenyl ester;
 [5-(2-Methyl-4,5-diphenyl-imidazol-1-yl)-pentyl]-carbamic acid ethyl ester;
 [5-(2-Methyl-4,5-diphenyl-imidazol-1-yl)-pentyl]-carbamic acid phenyl ester;
 [5-(2-Methyl-4,5-diphenyl-imidazol-1-yl)-pentyl]-carbamic acid 4-fluoro-phenyl ester;
 [5-(2-Methyl-4,5-diphenyl-imidazol-1-yl)-pentyl]-carbamic acid 2,4-difluoro-phenyl ester;
 [5-(2-Methyl-4,5-diphenyl-imidazol-1-yl)-pentyl]-carbamic acid 2-fluoro-phenyl ester;
 [5-(2-Methyl-4,5-diphenyl-imidazol-1-yl)-pentyl]-carbamic acid 4-chloro-phenyl ester;
 [5-(2-Methyl-4,5-diphenyl-imidazol-1-yl)-pentyl]-carbamic acid 4-methoxy-phenyl ester;
 [5-(2-Methyl-4,5-diphenyl-imidazol-1-yl)-pentyl]-carbamic acid o-tolyl ester;
 [5-(2-Methyl-4,5-diphenyl-imidazol-1-yl)-pentyl]-carbamic acid 4-cyano-phenyl ester;
 [5-(2-Methyl-4,5-diphenyl-imidazol-1-yl)-pentyl]-carbamic acid 2-methoxy-phenyl ester;
 [6-(2-Methyl-4,5-diphenyl-imidazol-1-yl)-hexyl]-carbamic acid 3,4-difluoro-phenyl ester;
 [6-(2-Methyl-4,5-diphenyl-imidazol-1-yl)-hexyl]-carbamic acid isopropyl ester;
 {6-[4,5-Bis-(4-fluoro-phenyl)-2-methyl-imidazol-1-yl]-hexyl}-carbamic acid 2-fluoro-phenyl ester;
 {6-[4,5-Bis-(4-fluoro-phenyl)-2-methyl-imidazol-1-yl]-hexyl}-carbamic acid 2,6-difluoro-phenyl ester;
 [6-(2-Methyl-4,5-diphenyl-imidazol-1-yl)-hexyl]-carbamic acid ethyl ester;
 [Benzaldehyde, O-[6-(2-methyl-4,5-diphenyl-1H-imidazol-1-yl)hexyl]amino]carbonyl]oxime;
 Benzaldehyde, O-[6-(2-methyl-4,5-diphenyl-1H-imidazol-1-yl)hexylaminocarbonyl]oxime;

 {6-[4,5-Bis-(4-fluoro-phenyl)-2-methyl-imidazol-1-yl]-hexyl}-carbamic acid 2-fluoro-phenyl ester;
 or
 [1-Methyl-6-(2-methyl-4,5-diphenyl-imidazol-1-yl)-hexyl]-carbamic acid 2-fluoro-phenyl ester.

According to various embodiments of a second aspect of the present invention are provided pharmaceutical formulations comprising compounds of Formula (I) as defined herein.

According to various embodiments of a third aspect of the present invention are provided methods of treating conditions the treatment of which can be effected by the inhibition of FAAH by the administration of pharmaceutical compositions comprising compounds of Formula (I) as defined herein.

According to another embodiment of the third aspect of the present invention is provided a method of treating pain, more particularly chronic pain, acute pain and neuropathic pain by the administration of pharmaceutical compositions comprising compounds of Formula (I) as defined herein.

According to another embodiment of the third aspect of the present invention is provided a method of treating pain, more particularly chronic pain, acute pain and neuropathic pain by the administration of a pharmaceutical composition comprising

or salt or solvate thereof.

According to another embodiment of the third aspect of the present invention is provided a method of treating neuropathic pain by the administration of a pharmaceutical composition comprising

or salt or solvate thereof.

According to another embodiment of the third aspect of the present invention is provided a method of providing neuroprotection and contraception and yet further methods of psychomotor disorder, hypertension, cardiovascular disease, eating disorder, nausea, AIDS-related complex, glaucoma, inflammation, psoriasis and multiple sclerosis by the administration of pharmaceutical compositions comprising compounds of Formula (I) as defined herein. See 60

Palmer, et al., “Natural and Synthetic Endocannabinoids and Their Structure-Activity Relationships,” *Current Pharmaceutical Design*, 2000, Vol. 6, No. 13, pp. 1381–1397 (p. 1386).

Other embodiments of the present invention may comprise a suitable combination of two or more of embodiments and/or aspects disclosed herein.

Yet other embodiments and aspects of the invention will be apparent according to the description provided below.

BRIEF DESCRIPTION OF THE FIGURES

FIG. 1A illustrates results from a rat formalin model used for testing acute chemo-induced pain. The single asterisk (*) applies when p is less than 0.05.

FIG. 1B illustrates results from a rat formalin model used for testing chronic chemo-induced pain. The single asterisk (*) applies when p is less than 0.05.

FIG. 2 illustrates results from the Hargreaves Test used for measuring acute thermal pain. The single asterisk (*) applies when p is less than 0.05 whereas the double asterisk (**) applies when p is less than 0.01. $n=6$.

FIG. 3 illustrates results from the Chung Model used for measuring neuropathic pain. The single asterisk (*) applies when p is less than 0.05 whereas the double asterisk (**) applies when p is less than 0.01. $n=9-10$.

DETAILED DESCRIPTION OF THE INVENTION

The description of the invention herein should be construed in congruity with the laws and principles of chemical bonding. For example, when a moiety is optionally substituted and said substitution requires the removal of a hydrogen atom from the moiety to be substituted, the description of the moiety should be read to include the moiety with or without said hydrogen atom. As another example, if a variable is defined as a particular moiety or atom and is further defined to have value of 0 or some integer, the bond(s) attaching said moiety should be suitably removed in the event the variable equals 0. An embodiment or aspect which depends from another embodiment or aspect, will describe only the variables having values and provisos that differ from the embodiment or aspect from which it depends. It is to be understood that the present invention may include any and all possible stereoisomers, geometric isomers, diastereoisomers, enantiomers, anomers and optical isomers, unless a particular description specifies otherwise. As used herein, "halo" or "halogen" includes fluoro, chloro, bromo and iodo. As used herein, "alkyl" or "alkylene" includes straight or branched chain configurations.

The compounds of this invention can exist in the form of pharmaceutically acceptable salts. Such salts include addition salts with inorganic acids such as, for example, hydrochloric acid and sulfuric acid, and with organic acids such as, for example, acetic acid, citric acid, methanesulfonic acid, toluenesulfonic acid, tartaric acid and maleic acid. Further, in case the compounds of this invention contain an acidic group, the acidic group can exist in the form of alkali metal salts such as, for example, a potassium salt and a sodium salt; alkaline earth metal salts such as, for example, a magnesium salt and a calcium salt; and salts with organic bases such as a triethylammonium salt and an arginine salt. The compounds of the present invention may be hydrated or non-hydrated.

The compounds of this invention can be administered in such oral dosage forms as tablets, capsules (each of which includes sustained release or timed release formulations), pills, powders, granules, elixirs, tinctures, suspensions, syrups and emulsions. The compounds of this invention may also be administered intravenously, intraperitoneally, subcutaneously, or intramuscularly, all using dosage forms well known to those skilled in the pharmaceutical arts. The 5 compounds can be administered alone, but generally will be administered with a pharmaceutical carrier selected upon the basis of the chosen route of administration and standard pharmaceutical practice. Compounds of this invention can also be administered in intranasal form by topical use of 10 suitable intranasal vehicles, or by transdermal routes, using transdermal skin patches. When compounds of this invention are administered transdermally the dosage will be 15 continuous throughout the dosage regimen.

The dosage and dosage regimen and scheduling of a
25 compounds of the present invention must in each case be
carefully adjusted, utilizing sound professional judgment
and considering the age, weight and condition of the
recipient, the route of administration and the nature and
extent of the disease condition. In accordance with good
30 clinical practice, it is preferred to administer the instant
compounds at a concentration level which will produce
effective beneficial effects without causing any harmful or
untoward side effects.

35 Compounds of the present invention may be synthesized according to the description provided below. Variables provided in the schema below are defined in accordance with the description of compounds of Formula (I) unless otherwise specified.

EXPERIMENTALS

Scheme 1

-continued

C

D

Reaction conditions: (i) aldehyde, $\text{CH}_3\text{COONH}_4$, CH_3COOH , 100°C ; (ii) bromide, NaH , DMP, rt; (iii) NaOH , EtOH , rt; (iv) (a) $\text{N}_3\text{P}(\text{O})(\text{OPh})_2$, Et_3N , toluene, 205°C . (b) R_3OH , 80°C .

The following Intermediates 1–13 may be used to synthesize Examples 1–51.

Intermediate 1

2-Methyl-4,5-diphenyl-1H-imidazole: (Scheme 1, (A))
 To a solution of benzil (3.0 g, 14 mmol) in glacial acetic acid (100 mL) was added ammonium acetate (22.2 g, 284 mmol) followed with acetaldehyde (1.26 g, 28 mmol). The resultant suspension was stirred at 100°C . for 2.5 hours. After removal of most of solvent, the residue was dissolved in EtOAc . The precipitate ammonium acetate was filtered off. The filtrate was washed with 2N NaOH , H_2O , and then was dried over MgSO_4 . After filtration and concentration in vacuo, the residue was purified by flash chromatography (SiO_2 ; $\text{EtOAc}/\text{Hexanes}$). This compound was obtained as a white solid (0.96 g, 4.1 mmol, 29% yield): mp 232–235°C.; MS m/e 235.0 (MH^+); ^1H NMR (DMSO-d_6) δ 7.27 (br m, 10H), 2.33 (s, 3H); ^{13}C NMR (DMSO-d_6) δ 144.3, 128.7, 128.3, 127.8, 127.3, 126.3, and 14.0. Anal. Calcd for $\text{C}_{16}\text{H}_{14}\text{N}_2 \cdot 0.12\text{H}_2\text{O}$: C, 81.26; H, 6.07; N, 11.85. Found: C, 81.20; H, 6.03; N, 11.89.

50

7-(2-Methyl-4,5-diphenyl-imidazol-1-yl)-heptanoic acid ethyl ester: (Scheme 1, (B)) To a solution of 2-methyl-4,5-diphenyl-1H-imidazole (0.20 g, 0.85 mmol) in DMF (6 mL) was added NaH (60% in mineral oil, 0.038 g, 0.94 mmol). The resulting mixture was stirred at rt for 10 min. The stirring continued for 2 hours after addition of ethyl 7-bromoheptanoate (0.21 g, 0.90 mmol). The reaction mixture was diluted with diethyl ether (30 mL), washed by water, and then was dried over MgSO_4 . After filtration and concentration in vacuo, the residue was purified by flash chromatography (SiO_2 ; $\text{EtOAc}/\text{Hexanes}$). This compound was obtained as a colorless oil (0.24 g, 0.61 mmol, 72% yield): ^1H NMR (DMSO-d_6) δ 1.08 (m, 4H), 1.15 (t, $J=7.2$ Hz, 3H), 1.33 (m, 4H), 2.16 (t, $J=6.6$ Hz, 2H), 2.40 (s, 3H), 3.68 (t, $J=7.8$ Hz, 2H), 4.03 (q, $J=4.5$ Hz, 2H), 7.05 (m, 1H), 7.13 (m, 2H), 7.34 (m, 4H), 7.48 (m, 3H); ^{13}C NMR (DMSO-d_6) δ 13.4, 14.4, 24.3, 25.7, 27.8, 29.6, 33.5, 43.3,

37

The following Intermediates 14–20 may be used to synthesize Examples 52–74.

Intermediate 14

1-(5-Bromo-penty1)-2-methyl-4,5-diphenyl-1H-imidazole: (Scheme 2 (E)) To a solution of 2-Methyl-4,5-diphenyl-1H-imidazole (2.0 g, 8.5 mmol) and 1,5-dibromopentane (3.01 g, 12.7 mmol) in DMF (100 mL) was added NaH (60% in mineral oil, 0.50 g, 12.7 mmol). The resulting mixture was stirred at rt for 1 hour, quenched by addition of water, extracted by CH_2Cl_2 , washed by water, and then was dried over MgSO_4 . After filtration and concentration in vacuo, the residue was purified by flash chromatography (SiO_2 ; EtOAc/Hexanes). This compound was obtained as a pale yellow oil (2.2 g, 5.7 mmol, 67% yield): ^1H NMR (DMSO): δ 1.20 (m, 2H), 1.47 (m, 2H), 1.64 (m, 2H), 2.41 (s, 3H), 3.45 (t, 2H), 3.72 (t, 2H), 7.16 (m, 3H), 7.31 (m, 4H), 7.55 (t, 3H). Mass Spec: 384.57 (MH^+).

Intermediate 15

1-(6-Bromo-hexyl)-2-methyl-4,5-diphenyl-1H-imidazole: (Scheme 2 (E)) Prepared as described for the example above. ^1H NMR (DMSO): δ 1.2 (m, 4H), 1.5 (m, 2H), 1.75 (m, 2H), 2.5 (s, 3H), 3.4 (t, 2H), 3.69 (t, 2H), 7.14 (m, 3H), 7.36 (m, 4H), 7.516 (m, 3H). Mass Spec: 399.14 (MH^+).

Intermediate 16

1-(3-Bromo-propyl)-2-methyl-4,5-diphenyl-1H-imidazole: (Scheme 2 (E)) Prepared as described for the example above. ^1H NMR (DMSO): δ 1.99 (m, 2H), 2.43 (s, 3H), 3.39 (t, 2H), 3.88 (t, 2H), 7.17 (m, 3H), 7.35 (m, 4H), 7.53 (m, 3H). Mass Spec: 356.59 (MH^+).

38

Intermediate 17

4-[3-(2-Methyl-4,5-diphenyl-imidazol-1-yl)-propoxy]-benzoic acid ethyl ester: (Scheme 2 (H)) To a solution of 1-(3-Bromo-propyl)-2-methyl-4,5-diphenyl-1H-imidazole (0.80 g, 2.2 mmol) and ethyl 4-hydroxybenzoate (1.20 g, 7.2 mmol) in DMF (30 mL) was added K_2CO_3 (0.40 g, 2.9 mmol). The resulting mixture was stirred at 55° C. for 1 hour, quenched by addition of water, extracted by EtOAc, washed by water, and then was dried over MgSO_4 . After filtration and concentration in vacuo, the residue was purified by flash chromatography (SiO_2 ; EtOAc/Hexanes). This compound was obtained as a pale yellow gum (0.92 g, 2.0 mmol, 94% yield): ^1H NMR (DMSO): δ 1.32 (t, 3H), 1.85 (m, 2H), 2.402 (s, 3H), 3.87 (m, 4H), 4.28 (q, 2H), 6.89 (d, J =8.82 Hz, 2H), 7.143 (m, 3H), 7.36 (m, 4H), 7.46 (m, 3H), 7.82 (d, J =8.85 mHz, 2H). Mass spec: 441.28 (MH^+).

Intermediate 18

4-[2-(2-Methyl-4,5-diphenyl-imidazol-1-yl)-ethoxy]-benzoic acid ethyl ester: (Scheme 2 (H)) Prepared as described for the example above. ^1H NMR (DMSO): δ 1.31 (t, 3H), 2.5 (s, 3H), 4.07 (m, 2H), 4.15 (m, 2H), 4.26 (q, 2H), 6.91 (d, J =8.88 mHz, 2H), 7.16 (m, 3H), 7.33 (d, J =7.56 mHz, 2H), 7.41 (m, 2H), 7.53 (m, 3H), 7.85 (d, J =8.85 mHz, 2H).

Intermediate 19

4-[3-(2-Methyl-4,5-diphenyl-imidazol-1-yl)-propoxy]-benzoic acid: (Scheme 2 (I)) To a solution of 4-[3-(2-Methyl-4,5-diphenyl-imidazol-1-yl)-propoxy]-benzoic acid ethyl ester (0.80 g, 1.8 mmol) in EtOH (20 mL) was added NaOH (10 N, 4.0 mL, 40.0 mmol). The resulting mixture was stirred at rt for 3 hours, diluted with water, acidified to

39

pH~1 using 1N HCl, extracted by CH_2Cl_2 , and then was dried over MgSO_4 . After filtration and concentration in vacuo, the residue was purified by flash chromatography (SiO_2 ; $\text{MeOH}/\text{CH}_2\text{Cl}_2$). This compound was obtained as a white dry foam in HCl salt form (0.80 g, 1.8 mmol, 99% yield): ^1H NMR (DMSO): δ 1.93 (m, 2H), 2.67 (s, 3H), 3.97 (t, 2H), 4.13 (t, 2H), 6.85 (d, $J=8.82$ mHz, 2H), 7.33 (s, 5H), 7.43 (m, 2H), 7.55 (m, 3H), 7.86 (d, $J=8.82$ mHz, 2H), 12.64 (b, 1H).

Intermediate 20

4-[2-(2-Methyl-4,5-diphenyl-imidazol-1-yl)-ethoxy]benzoic acid: (Scheme 2 (I)) Prepared as described for the example above. ^1H NMR (DMSO): δ 2.82 (s, 3H), 4.19 (m, 2H), 4.39 (m, 2H), 6.93 (d, $J=8.85$ mHz, 2H), 7.359 (m, 5H), 7.54 (m, 2H), 7.61 (m, 3H), 7.86 (d, $J=8.76$ mHz, 2H), 12.685 (b, 1H).

EXAMPLE 52

{4-[2-(2-Methyl-4,5-diphenyl-imidazol-1-yl)-ethoxy]phenyl}-carbamic acid 3,4-difluoro-phenyl ester: (Scheme 2 (J)) To a suspension of 4-[2-(2-Methyl-4,5-diphenyl-imidazol-1-yl)-ethoxy]benzoic acid (0.10 g, 0.23 mmol) in a mixture of Et_3N (0.09 g, 0.88 mmol) and toluene (2 mL) was added azide (0.1 g, 0.35 mmol). The resultant mixture was stirred at r.t. for 10 min. and then at 108°C . under N_2 for 45 min. After the mixture was cooled to r.t., 3,4-difluorophenol (0.10 g, 1.0 mmol) was added. The reaction mixture was stirred at r.t. for 10 min and then at 80°C . for 1 h. The mixture was diluted with EtOAc , washed with H_2O . After filtration and concentration in vacuo, the residue was purified by preparative HPLC (YMC 30 $\times$ 100 mm (5 μM packing), 10% $\text{MeOH}/90\%$ water/01% TFA as mobile phase A, 90% $\text{MeOH}/10\%$ water/0.1% TFA as mobile phase B). This compound was obtained as a white solid (0.082 g, 0.13 mmol, 55% yield): ^1H NMR (DMSO): δ 82.83 (s, 3H), 4.06 (t, 2H), 4.39 (t, 2H), 6.82 (d, $J=7.05$ mHz, 2H), 7.29 (m, 2H), 7.32 (m, 2H), 7.45 (m, 4H), 7.52 (m, 4H), 7.61 (m, 3H). Mass Spec: 526.22 (MH^+).

40

EXAMPLE 53

{4-[2-(2-Methyl-4,5-diphenyl-imidazol-1-yl)-ethoxy]phenyl}-carbamic acid 4-chloro-phenyl ester: (Scheme 2 (J)) Prepared as described for the example above. ^1H NMR (DMSO): δ 82.83 (s, 3H), 4.07 (t, 2H), 4.39 (t, 2H), 6.83 (d, $J=10.3$ mHz, 2H), 7.24 (d, $J=10.3$ mHz, 2H), 7.30 (m, 2H), 7.36 (m, 5H), 7.46 (d, $J=12.6$ mHz, 2H), 7.59 (m, 2H), 7.61 (m, 3H). Mass Spec: 524.18 (MH^+).

EXAMPLE 54

{4-[2-(2-Methyl-4,5-diphenyl-imidazol-1-yl)-ethoxy]phenyl}-carbamic acid methyl ester: (Scheme 2 (J)) Prepared as described for the example above. ^1H NMR (DMSO): δ 82.82 (s, 3H), 3.62 (s, 3H), 4.05 (t, 2H), 4.38 (t, 2H), 6.77 (d, $J=7$ mHz, 2H), 7.28 (m, 1H), 7.31 (m, 3H), 7.36 (m, 3H), 7.53 (m, 2H), 7.61 (m, 3H), 9.45 (b, 1H). Mass Spec: 428.24 (MH^+).

EXAMPLE 55

{4-[3-(2-Methyl-4,5-diphenyl-imidazol-1-yl)-propoxy]phenyl}-carbamic acid 3,4-difluoro-phenyl ester: (Scheme 2 (J)) Prepared as described for the example above. Analytical HPLC 1.66 min (95%). Mass Spec: 540.25 (MH^+).

41
EXAMPLE 56{4-[3-(2-Methyl-4,5-diphenyl-imidazol-1-yl)-propoxy]-phenyl}-carbamic acid 4-methoxy-phenyl ester: (Scheme 2 (J)) Prepared as described for the example above. Analytical HPLC 1.52 min (98%). Mass Spec: 534.35 (MH⁺).

EXAMPLE 57

{4-[3-(2-Methyl-4,5-diphenyl-imidazol-1-yl)-propoxy]-phenyl}-carbamic acid 4-chloro-phenyl ester: (Scheme 2 (J)) Prepared as described for the example above. Analytical HPLC 1.62 min (81%). Mass Spec: 538.22 (MH⁺).

Reaction conditions: (i) $[(\text{CH}_2)_3\text{Si}]_2\text{NNa}$, THF, R_2Si , -78° C . to rt.; (ii) NaOH , MeOH , Reflux; (iii) (a) $\text{N}_3\text{P}(\text{O})(\text{OPh})_2$, Et_3N , toluene, 108° C , (b) 2-fluorophenol, 100° C .

The following Intermediates 21–24 may be used to synthesize Examples 75–77.

Intermediate 21

2-Methyl-7-(2-methyl-4,5-diphenyl-imidazol-1-yl)-heptanoic acid ethyl ester: (Scheme 3 (O)) Sodium bis(trimethylsilyl)amide (1M in THF) (3.0 ml, 3.0 mmole) was added dropwise to a solution of starting material 7-(2-

2-Isopropyl-7-(2-methyl-4,5-diphenyl-imidazol-1-yl)-
65 heptanoic acid ethyl ester: (Scheme 3 (O)) Sodium bis
(trimethylsilyl)amide (1M in THF) (1.2 ml, 1.2 mmole) was
added dropwise to a solution 7-(2-Methyl-4,5-diphenyl-

46

Methyl-4,5-diphenyl-imidazol-1-yl)-heptanoic acid ethyl ester (1 g, 2.5 mmole) in anhydrous THF (10 ml) at -78°C. under Nitrogen. After addition, the reaction was let stirred 20 minutes, then Iodomethane (0.06 ml, 0.96 mmole) was added slowly at -78° under Nitrogen. The reaction mixture was let stirred at -78°C. for 1 hr, then warming up to room temperature and let stirred for 18 hrs. The next day, analysis by TLC indicated consumption of starting material. The reaction was quenched with aqueous Ammonium Chloride (10 ml). The aqueous layer was extracted with Ethyl Acetate (3×25 ml). The organic layers obtained were combined, dried over Sodium Sulfate and filtered. The resultant filtrate was concentrated in vacuo. Purification by flash column chromatography using Hexane/Ethyl Acetate (4:1) gave rise to product (150 mg, 45%). ^1H NMR (CDCl_3): δ 1.09 (d, $J=6.95$ mHz, 6H), 1.15 (t, 3H), 1.51 (m, 2H), 2.32 (m, 1H), 2.50 (s, 3H), 3.70 (t, 2H), 4.11 (q, 2H), 7.25 (m, 3H), 7.32 (m, 2H), 7.45 (m, 5H), ^{13}C NMR (CDCl_3): δ 13.7, 14.3, 17.1, 26.4, 26.6, 30.3, 33.4, 39.4, 43.8, 60.2, 125.9, 126.5, 128.0, 128.4, 128.5, 129.0, 131.1, 131.8, 134.8, 136.3, 144.0, 176.6. Anal. Calcd. for $\text{C}_{26}\text{H}_{32}\text{N}_2\text{O}_2$ 0.25 H_2O : C, 76.34; H, 8.01; N, 6.85. Found: C, 76.38; H, 8.13; N, 6.83. Mass Spec: 405.29 (MH $^+$).

Intermediate 22

35 2-Ethyl-7-(2-methyl-4,5-diphenyl-imidazol-1-yl)-heptanoic acid ethyl ester: (Scheme 3 (O)) This compound was obtained using the procedures as described above. The following scales and reagents were used: 7-(2-Methyl-4,5-diphenyl-imidazol-1-yl)-heptanoic acid ethyl ester (390 mg, 40 1 mmole), Sodium bis(trimethylsilyl)amide (1M in THF) (1.2 ml, 1.2 mmole), Iodoethane (0.4 ml, 779.8 mg, 5 mmole), anhydrous THF (10 ml). Product was obtained (100 mg, 24%). ^1H NMR (CDCl_3): 80.88 (t, 3H), 1.23 (m, 4H), 1.33 (t, 3H), 1.54 (m, 4H), 1.68 (b, 1H), 2.04 (s, 1H), 2.17 (m, 1H), 2.49 (s, 3H), 3.709 (t, 2H), 4.15 (m, 2H), 7.19 (m, 3H), 7.42 (m, 3H), 7.46 (m, 4H). ^{13}C NMR (CDCl_3): 812.0, 13.9, 14.6, 25.7, 26.6, 27.0, 30.5, 31.9, 44.0, 47.3, 60.2, 126.1, 126.7, 128.2, 128.7, 129.2, 131.3. Anal. Calcd. for $\text{C}_{27}\text{H}_{34}\text{N}_2\text{O}_2$: C, 77.48; H, 8.19; N, 6.69. Found: C, 77.34; N, 8.01; N, 6.56. Mass Spec: 419.32 (MH^+).

Intermediate 23

47

imidazol-1-yl)-heptanoic acid ethyl ester (390 mg, 1 mmole) in anhydrous THF (10 ml) at -78° C. under Nitrogen. The reaction solution was let stirred warming up to room temperature during a period of 3 hrs. The reaction solution was cooled to -78° C., and 2-Iodopropane (499.97 ul, 849.95 mg, 5 mmole) was added in dropwise. The reaction was let stirred at room temperature for 1 hr, then at 50° C. for 1 hr. Analysis by TLC indicated consumption of starting material. The reaction was worked-up using the procedures as described above. Crude material was purified by flash column chromatography using Hexane/Ethyl Acetate (4:1) to give product (80 mg, 18.5%). ¹H NMR (CDCl₃): δ 0.89 (t, 6H), 1.14 (m, 4H), 1.249 (t, 3H), 1.49 (m, 3H), 1.81 (m, 2H), 1.989 (m, 1H), 2.49 (s, 3H), 3.70 (t, 2H), 4.1 (m, 2H), 7.15 (m, 1H), 7.31 (t, 2H), 7.40 (m, 2H), 7.445 (m, 5H). ¹³C NMR (CDCl₃): δ 131.7, 14.4, 20.2, 20.4, 26.5, 27.2, 29.3, 30.3, 30.7, 43.8, 52.6, 59.9, 125.9, 126.5, 128.0, 128.3, 128.5, 129.0, 131.0, 131.8, 134.8, 136.3, 144.0, 175.6. Anal. Calcd. for C₂₈H₃₆N₂O₂: 0.21 H₂O: C, 77.07, H, 8.41; N, 6.42. Found: C, 77.08; H, 8.84; N, 6.22. Mass Spec: 433.2 (MH⁺).

Intermediate 24

2-Methyl-7-(2-methyl-4,5-diphenyl-imidazol-1-yl)-heptanoic acid: (Scheme 3 (P)) A solution of starting material 2-Methyl-7-(2-methyl-4,5-diphenyl-imidazol-2-yl)-heptanoic acid ethyl ester (130 mg, 0.32 mmole) in Methanol (5 ml) and Sodium Hydroxide (64 mg, 1.61 mmole) was let stirred under reflux for 18 hrs. The next day, the reaction was let cooled to room temperature and concentrated in vacuo. The residue was diluted with water, and acidified with Hydrochloric Acid (3N). The aqueous layer was extracted with Dichloromethane (3×10 ml). The organic layers were combined, dried over Sodium Sulfate and filtered. The resultant filtrate was concentrated in vacuo to afford product as a white solid (120 mg, 99%). Mass Spec: 377 (MH⁺).

Intermediate 25

2-Ethyl-7-(2-methyl-4,5-diphenyl-imidazol-1-yl)-heptanoic acid: (Scheme 3 (P)) This compound was obtained

48

using the procedures as described above. The following scales and reagents were used: 2-Ethyl-7-(2-methyl-4,5-diphenyl-imidazol-1-yl)-heptanoic acid ethyl ester (100 mg, 0.24 mmole), Sodium hydroxide (2N, 0.5 mL, 1.0 mmole), Methanol (5 mL). Product was obtained as white solid (90 mg, 96%). Mass Spec: 391.25 (MH⁺).

Intermediate 26

2-Ethyl-7-(2-methyl-4,5-diphenyl-imidazol-1-yl)-heptanoic acid: (Scheme 3 (P)) This compound was obtained using the procedures as described above. The following scales and reagents were used: 2-Isopropyl-7-(2-methyl-4,5-diphenyl-imidazol-1-yl)-heptanoic acid ethyl ester (80 mg, 0.18 mmole), Sodium hydroxide (2N, 0.5 mL, 1.0 mmole), Methanol (5 mL). Product was obtained as white solid (46 mg, 64%). Mass Spec: 405.37 (MH⁺).

EXAMPLE 71

[1-Methyl-6-(2-methyl-4,5-diphenyl-imidazol-1-yl)-hexyl]-carbamic acid 2-fluoro-phenyl ester: (Scheme 3 (Q)) Diphenylphosphoryl Azide (0.083 ml, 0.38 mmole) was added to a suspension of starting material 2-methyl-7-(2-methyl-4,5-diphenyl-imidazol-1-yl)-heptanoic acid (120 mg, 0.32 mmole) and Triethylamine (0.14 ml, 1.005 mmole) in Toluene (5 ml) at room temperature. The reaction mixture was let stirred at room temperature for 10 minutes under Nitrogen, then at 108° C. for 90 minutes. The reaction was let cooled to room temperature, to which 2-Fluorophenol (0.03 ml, 0.038 g, 0.338 mmole) was added. The reaction mixture was let stirred at room temperature for 30 minutes, then at 100° C. for 18 hrs. The next day, analysis by TLC (Dichloromethane/Ethyl Acetate 3:1) indicated consumption of starting material. The reaction was let cooled to room temperature, where the solvent was removed by rotovap. The crude material was purified by flash column chromatography using Dichloromethane/Ethyl Acetate (6:1 to 3:1). Product was obtained (110 mg, 71%). ¹H NMR (CDCl₃): δ 1.21 (d, J=8.75 Hz, 6H), 1.35 (m, 2H), 1.51 (m, 2H), 2.50 (s, 3H), 3.71 (m, 3H), 4.93 (b, 1H), 7.18 (m, 6H), 7.32 (m,

49

2H), 7.46 (m, 6H). ^{13}C NMR (CDCl_3): 813.7, 21.1, 25.2, 30.3, 36.7, 43.7, 47.5, 116.5, 116.650, 124.132, 124.325, 125.943, 126.520, 128.027, 128.347, 128.509, 129.018, 131.101, 131.796, 134.8, 136.4, 138.6, 144.1, 153.0, 153.7, 155.6. Anal. Calcd. for $\text{C}_{30}\text{H}_{32}\text{FN}_3\text{O}_2$ 0.42 H_2O : C, 73.06; H, 6.71; N, 8.52. Found: C, 73.24; H, 6.82; N, 8.29. Mass Spec: 486.27 (MH^+).

EXAMPLE 72

[1-Ethyl-6-(2-methyl-4,5-diphenyl-imidazol-1-yl)-hexyl]-carbamic acid 2-fluoro-phenyl ester: (Scheme 3 (Q))
This compound was prepared using the procedures as described above. The following scales and reagents were used: Starting material 2-ethyl-7-(2-methyl-4,5-diphenyl-imidazol-1-yl)-heptanoic acid (90 mg, 0.23 mmole). Diphenylphosphoryl Azide (0.060 ml, 0.276 mmole), Triethylamine (0.14 ml, 1.005 mmole), and 2-Fluorophenol (30 μl , 0.338 mmole). After purification by flash column chromatography, product was obtained (90 mg, 18%). ^1H NMR (CDCl_3): 80.96 (t, 3H), 1.24 (m, 5H), 1.51 (m, 2H), 1.54 (m, 3H), 2.50 (s, 3H), 3.72 (t, 2H), 4.77 (d, $J=9.28$ mHz, 1H), 7.16 (m, 7H), 7.342 (m, 2H), 7.45 (m, 5H). ^{13}C NMR (CDCl_3): 810.2, 13.7, 25.1, 26.3, 28.2, 30.3, 34.7, 43.7, 53.076, 116.466, 116.650, 124.108, 124.276, 125.937, 126.527, 128.015, 128.348, 128.483, 129.001, 131.1, 131.8, 134.8, 136.3, 144.1, 153.5. Anal. Calcd. for $\text{C}_{31}\text{H}_{34}\text{FN}_3\text{O}_2$: C, 74.52; H, 6.86; N, 8.41. Found: C, 74.43; H, 6.98; N, 8.32. Mass Spec: 500.34 (MH^+).

EXAMPLE 73

[1-Isopropyl-6-(2-methyl-4,5-diphenyl-imidazol-1-yl)-hexyl]-carbamic acid 2-fluoro-phenyl ester: (Scheme 3 (Q))
This compound was obtained using the procedures as described above. The following scales and reagents were used: Starting material 2-isopropyl-7-(2-methyl-4,5-diphenyl-imidazol-1-yl)-heptanoic acid (45.8 mg, 0.113

50

mmole), Diphenylphosphoryl Azide (0.029 ml, 0.135 mmole), Triethylamine (0.049 ml, 0.351 mmole), and 2-Fluorophenol (0.012 ml, 0.135 mmole). After purification by flash column chromatography, product was obtained (27.5 mg, 47%). ^1H NMR (CDCl_3): 80.95 (m, 6H), 1.27 (m, 5H), 1.53 (m, 2H), 1.73 (m, 2H), 2.50 (s, 3H), 3.56 (m, 1H), 3.73 (t, 2H), 4.75 (d, $J=10$ mHz, 1H), 7.19 (m, 7H), 7.33 (m, 2H), 7.45 (m, 5H). ^{13}C NMR (CDCl_3): 813.7, 17.5, 19.3, 25.5, 26.3, 30.3, 32.2, 32.3, 43.7, 56.7, 116.5, 116.6, 124.1, 124.3, 124.3, 125.9, 126.4, 126.5, 128.0, 128.3, 128.5, 128.8, 131.1, 131.8, 134.8, 136.4, 144.1, 153.7, Anal. Reaction conditions: (i) (a) NaH, DMF, rt. (b) diethyl phenyl maleate, 45–50° C. (ii) NaOH, THF, 80° C.; (iii) CH₃COOH, reflux; (iv) (a) $\text{N}_3\text{P}(\text{O})(\text{OPh})_2$, Et₂N, toluene, 108° C., (b) 2-fluorophenol, 100° C.

The following Intermediates 27–29 may be used to synthesize Example 78.

Intermediate 27

2-[5-(2-Methyl-4,5-diphenyl-imidazol-1-yl)-penty]-2-phenyl-malonic acid diethyl ester: (Scheme 4 (R)) A solution of starting material 1-(5-bromo-penty)-2-methyl-4,5-diphenyl-1H-imidazole (0.5 g, 1.3 mmole) in DMF (5 ml) was added to a suspension of Sodium Hydride (63 mg, 1.56 mmole) in DMF (5 ml) at room temperature under Nitrogen. The reaction suspension was let stirred for 30 minutes at room temperature. Diethyl Phenyl Malonate (0.29 ml, 313.5 mg, 1.3 mmole) was added to the reaction suspension dropwise at room temperature under nitrogen. The reaction mixture was let stirred at 45–50° C. for 48 hrs. Analysis by TLC indicated only a trace of starting material remained. The reaction was let cooled to room temperature, then poured into saturated Sodium Chloride solution. The aqueous layer was extracted with Ethyl Acetate (3×25 ml). The organic layers were combined and washed with water (1×30 ml). The organic layer was separated, dried over Sodium Sulfate and filtered. The filtrate was concentrated in vacuo. The crude material was purified by flash column chromatography using Ethyl Acetate/Toluene (2.5:7.5). Product was obtained as a colorless oil (650 mg, 93%). ¹H NMR (CDCl₃): δ1.12 (m, 4H), 1.20 (t, 6H), 1.47 (m, 2H), 2.16 (t, 2H), 2.46 (s, 3H), 3.66 (t, 2H), 4.22 (m, 4H), 7.15 (m, 1H), 7.26 (m, 4H), 7.32 (m, 5H), 7.43 (m, 5H). ¹³C NMR (CDCl₃): δ13.7, 14.0, 24.2, 26.8, 30.2, 35.7, 43.8, 61.5, 62.5, 125.9, 126.5, 127.5, 127.9, 128.1, 128.2, 128.3, 128.5, 129.0, 131.0, 144.1, 170.6. Anal. Calcd. for C₃₄H₃₈N₂O₄·0.34 Toluene: C, 76.77; H, 7.20; N, 4.91. Found: C, 76.64; H, 7.27; N, 4.78. Mass Spec: 539.29 (MH⁺).

2-[5-(2-Methyl-4,5-diphenyl-imidazol-1-yl)-penty]-2-phenyl-malonic acid: (Scheme 4 (S)) A solution of starting material 2-[5-(2-methyl-4,5-diphenyl-imidazol-1-yl)-penty]-2-phenyl-malonic acid diethyl ester (630 mg, 1.17 mmole) in THF (18 ml) and Sodium hydroxide (2N) (8 ml) was let stirred at 80° C. for 18 hrs. The next day, analysis by TLC indicated no significant change in the reaction. The THF solvent was removed by rotovap. The residue was diluted in Methanol (20 ml). The reaction solution was let stirred under reflux for 2 hrs. Analysis by TLC indicated consumption of starting material. The organic solvent was removed by rotovap. The residue was diluted with water (20 ml). The aqueous layer was extracted Diethyl Ether (2×20 ml). The organic layers were combined and extracted with Sodium Hydroxide (10%) (2×10 ml). The basic aqueous layers were combined and acidified with Hydrochloric acid (3N) to pH=1, then extracted with dichloromethane (2×20 ml). The organic layers were combined, dried over Sodium Sulfate and filtered. The resultant filtrate was concentrated in vacuo to provide product as a white solid (580 mg, quantitative yield). Mass Spec: 483.54 (MH⁺).

Determination of FAAH Activity

Homogenates of crude membranes were prepared from H4 cells that express transfected human FAAH (H4-FAAH cells). Briefly, cells were grown in DMEM supplemented with 10% FBS and Geneticin at a final concentration of 500 µg/ml (Gibco BRL, Rockville, Md.). Confluent cultures of H4-FAAH cells were rinsed twice with phosphate-buffered saline [138 mM NaCl, 4.1 mM KCl, 5.1 mM Na₂PO₄, 1.5 mM KH₂PO₄ (pH 7.5), 37° C.] and incubated for 5–10 min. at 4° C. in lysis buffer [1 mM sodium bicarbonate]. Cells were transferred from plates to polypropylene tubes (16×100 mm), homogenized and centrifuged at 32,000×g for 30 min. Pellets were resuspended by homogenization in lysis buffer and centrifuged at 32,000×g for 30 min. Pellets were resuspended in lysis buffer (15–20 µg protein/ml) then stored at -80° C. until needed. On the day of an experiment, membranes were diluted to 2.67 µg protein/ml in 125 mM Tris-Cl, pH 9.0.

54

Activity of FAAH was measured using a modification of the method described by Omeir et al., 1995 (Life Sci 56:1999, 1995). Membrane homogenates (240 ng protein) were incubated at room temperature for one hour with 1.67 nM anandamide [³H]-ethanolamine 1-³H] (American Radiolabeled Chemical Inc., St Louis, Mo.) and 10 µM anandamide (Sigma/RBI, St. Louis, Mo.) in the absence and presence of inhibitors. The reaction was stopped by the addition of 1 volume of a solution of methanol and dichloroethane (1:1). The mixture was shaken and then centrifuged at 1000×g for 15 min. to separate the aqueous and organic phases. An aliquot of the aqueous phase, containing [³H]-ethanolamine was withdrawn and counted by scintillation spectroscopy. Data were expressed as the percentage of [³H]-ethanolamine formed versus vehicle, after subtraction of the background radioactivity determined in the presence of 10 µM arachidonoyl trifluoromethyl ketone (ATFMK), an inhibitor of FAAH. IC₅₀ values were determined using a four-parameter logistic equation for dose-response curves. Compounds for which IC₅₀ values are not provided herein showed no FAAH inhibition or marginal FAAH inhibition in preliminary tests.

In vivo results

In FIG. 1., example 1, was active in phase I (acute phase) and phase II (chronic phase) of the rat formalin test. In animals that received 25 mg/kg, i.v. of Example 1, the number of paw flinches was reduced by nearly 40% in the first 10 minutes after administration of formalin. Paw flinches were reduced by approximately 30% over the following 50 minutes. The effect of example 1 was similar to that seen with a 3 mg/kg, i.p. dose of morphine.

In FIG. 2., animals that received Example 1, the latency to paw withdrawal was increased significantly. The present results confirm, the activity of Example 1 against acute pain.

In FIG. 3., Example 1 was examined in the Chung model of neuropathic pain where animals exhibit a pain response (paw withdrawal) to a normally innocuous stimulus (light touch). In animals with a neuropathic injury, the threshold for withdrawal of the injured paw was increased (toward normal) in a dose-dependent fashion by Example 1. The anti-neuropathic effect observed with 20 mg/kg Example 1 exhibited earlier onset of action compared to 100 mg/kg gabapentin (reference compound) with similar peak efficacy.

What is claimed is:

[1. Compounds of Formula (I)]

and pharmaceutically acceptable salts and solvates thereof wherein

R¹ are R² are each independently H, C₁₋₃ alkyl or halo; R³ is C₁₋₃alkyl or C₃₋₇cycloalkyl;

A is L;

L is -phenyl-O—C₁₋₄alkylene wherein said C₁₋₄alkylene is attached to D;

provided that if A is L, then D is X(O)O and A—D is not interrupted with J—J', —Z-phenyl- or —Z—C₁₋₃alkylene;

D is X(O)O, X(O)N(G'), HYC(O)O or HYC(O)ON==C(G');

18. A method of treating chronic pain, acute pain or neuropathic pain in a mammal in need thereof by the administration of an effective amount of a pharmaceutical composition comprising a compound according to claims 1, 2, 3 or 4.]

19. A method of treating chronic pain, acute pain and neuropathic pain by the administration of a pharmaceutical composition comprising

or a pharmaceutically acceptable salt or solvate thereof.

20. A method of treating neuropathic pain by the administration of a pharmaceutical composition comprising

70

or a pharmaceutically acceptable salt or solvate thereof.

21. A compound of Formula (I)

or a pharmaceutically acceptable salt or solvate thereof
 wherein

*R*¹ and *R*² are each independently *H*, *C*₁₋₃alkyl or halo;

*R*³ is *C*₁₋₃alkyl or *C*₃₋₇cycloalkyl;

A is *C*₁₋₁₂alkylene or *L*;

L is -phenyl-*O*-*C*₁₋₄alkylene wherein said *C*₁₋₄alkylene is attached to *D*;

provided that if *A* is *L*, then *D* is *X*(*O*)*O* and *A*-*D* is not interrupted with *J*-*J'*, -*Z*-phenyl- or -*Z*-*C*₁₋₃alkylene;

D is *X*(*O*)*O*, *X*(*O*)*N*(*G'*), *HYC*(*O*)*O* or *HYC*(*O*)*ON*=*C*(*G'*);

X is *C* and is attached to *A*;

Y is *N* and is attached to *A*;

G is phenyl or -*C*₁₋₂alkylene-phenyl, said phenyl or phenyl of said -*C*₁₋₂alkylene-phenyl are substituted with fluoro;

G' is *H*, *C*₁₋₅alkyl or *C*₁₋₅haloalkyl; and

wherein *A*-*D* is optionally interrupted with *J*-*J'*, -*Z*-phenyl- or -*Z*-*C*₁₋₃alkylene;

wherein

Z is *O* or *S* and is attached to *A*;

J is *CH* and is attached to *A*, *D* and *J'*;

J' is *C*₁₋₄alkyl or phenyl;

provided that

if *A*-*D* is interrupted with -*Z*-phenyl-, then *A* is *C*₁₋₅alkylene;

if *A*-*D* is not interrupted with -*Z*-phenyl-, then *A* is *C*₅₋₁₂alkylene.

22. A compound of Formula (I)

or a pharmaceutically acceptable salt or solvate thereof
wherein

R¹ and R² are each independently H, C₁₋₃alkyl or halo;

R³ is C_{1-C₃}alkyl or C₃₋₇cycloalkyl;

A is C₁₋₁₂alkylene or L;

L is -phenyl-O—C₁₋₄alkylene wherein said C₁₋₄alkylene is attached to D;

provided that if A is L, then D is X(O)O and A—D is not interrupted with J—J', —Z-phenyl- or —Z—C₁₋₃alkylene;

D is X(O)O, X(O)N(G'), HYC(O)O or HYC(O)ON=C(G');

X is C and is attached to A;

Y is N and is attached to A;

G is phenyl or —C₁₋₂alkylene-phenyl, said phenyl or phenyl of said —C₁₋₂alkylene-phenyl are substituted with cyano;

G' is H, C₁₋₅alkyl or C₁₋₅haloalkyl; and

wherein A—D is optionally interrupted with J—J', —Z-phenyl- or —Z—C₁₋₃alkylene;

wherein

Z is O or S and is attached to A;

J is CH and is attached to A, D and J';

J' is C₁₋₄alkyl or phenyl;

provided that

if A—D is interrupted with —Z-phenyl-, then A is C₁₋₅alkylene;

if A—D is not interrupted with —Z-phenyl-, then A is C₅₋₁₂alkylene.

23. A compound of Formula (I)

or a pharmaceutically acceptable salt or solvate thereof
wherein

R¹ and R² are each independently H, C₁₋₃alkyl or halo;

R³ is C_{1-C₃}alkyl or C₃₋₇cycloalkyl;

A is L;

L is -phenyl-O—C₁₋₄alkylene wherein said C₁₋₄alkylene is attached to D;

D is X(O)O;

X is C and is attached to A; and

G is H, C₁₋₅alkyl, C₁₋₅haloalkyl, C₃₋₇cycloalkyl, phenyl, —C₁₋₂alkylene-phenyl, C-pyridyl or N-pyridyl, said

phenyl or —C₁₋₂alkylene-phenyl are each optionally and independently substituted with one or more of the same or different substituents selected from the group consisting of halo, NO₂, CN, —C(O)O—C₁₋₃alkyl, C₁₋₃alkyl, hydroxy and C₁₋₃alkoxy.

24. A compound of Formula (I)

or a pharmaceutically acceptable salt or solvate thereof
wherein

R¹ and R² are each independently H, C₁₋₃alkyl or halo;

R³ is C_{1-C₃}alkyl or C₃₋₇cycloalkyl;
A is C₁₋₁₂alkylene;

D is HYC(O)ON=C(G');

Y is N and is attached to A;

G is H, C₁₋₅alkyl, C₁₋₅haloalkyl, C₃₋₇cycloalkyl, phenyl, —C₁₋₂alkylene-phenyl, C-pyridyl or N-pyridyl, said phenyl or —C₁₋₂alkylene-phenyl are each optionally and independently substituted with one or more of the same or different substituents selected from the group consisting of halo, NO₂, CN, —C(O)O—C₁₋₃alkyl, C₁₋₃alkyl, hydroxy and C₁₋₃alkoxy; and

G' is H, C₁₋₅alkyl or C₁₋₅haloalkyl.

25. A compound of Formula (I)

or a pharmaceutically acceptable salt or solvate thereof
wherein

R¹ and R² are each independently H, C₁₋₃alkyl or halo;

R³ is C_{1-C₃}alkyl or C₃₋₇cycloalkyl;

A is C₁₋₁₂alkylene or L;

L is -phenyl-O—C₁₋₄alkylene wherein said C₁₋₄alkylene is attached to D;

provided that if A is L, then D is X(O)O and A—D is not interrupted with J—J', —Z-phenyl- or —Z—C₁₋₃alkylene;

D is X(O)O, X(O)N(G'), HYC(O)O or HYC(O)ON=C(G');

X is C and is attached to A;

Y is N and is attached to A;

G is —C₁₋₂alkylene-phenyl, said —C₁₋₂alkylene-phenyl is optionally substituted with one or more of the same or different substituents selected from the group consisting of halo, NO₂, CN, —C(O)O—C₁₋₃alkyl, C₁₋₃alkyl, hydroxy and C₁₋₃alkoxy;

G' is H, C₁₋₅alkyl or C₁₋₅haloalkyl; and

73

wherein $A-D$ is optionally interrupted with $J-J'$;
 $-Z\text{-phenyl-}$ or $-Z\text{-}C_{1-3}\text{alkylene}$;
wherein
 Z is O or S and is attached to A ;
 J is CH and is attached to A , D and J' ;
 J' is $C_{1-4}\text{alkyl}$ or phenyl ;

provided that

if $A-D$ is interrupted with $-Z\text{-phenyl-}$, then A is
 $C_{1-5}\text{alkylene}$;

if $A-D$ is not interrupted with $-Z\text{-phenyl-}$, then A is
 $C_{5-12}\text{alkylene}$.

26. A compound of Formula (I)

or a pharmaceutically acceptable salt or solvate thereof
wherein

R^1 and R^2 are each independently H , $C_{1-3}\text{alkyl}$ or halo ;

R^3 is $C_{1-3}\text{alkyl}$ or $C_{3-7}\text{cycloalkyl}$;

A is $C_{1-12}\text{alkylene}$ or L ;

L is $\text{-phenyl-}O-C_{1-4}\text{alkylene}$ wherein said
 $C_{1-4}\text{alkylene}$ is attached to D ;

provided that if A is L , then D is $X(O)O$ and $A-D$ is not
interrupted with $J-J'$, $-Z\text{-phenyl-}$ or $-Z\text{-}C_{1-3}$
alkylene;

D is $X(O)O$, $X(O)N(G')$, $HYC(O)O$ or $HYC(O)ON=C$
 (G') ;

X is C and is attached to A ;

Y is N and is attached to A ;

G is phenyl or $-C_{1-2}\text{alkylene-phenyl}$, said phenyl or
 phenyl of said $-C_{1-2}\text{alkylene-phenyl}$ are optionally
substituted with one or more of the same or different
substituents selected from the group consisting of halo ,
 CN , $-C(O)O-C_{1-3}\text{alkyl}$, $C_{1-3}\text{alkyl}$, and $C_{1-3}\text{alkoxy}$;

G' is H , $C_{1-5}\text{alkyl}$ or $C_{1-5}\text{haloalkyl}$; and

wherein $A-D$ is optionally interrupted with $J-J'$,
 $-Z\text{-phenyl-}$ or $-Z\text{-}C_{1-3}\text{alkylene}$;

wherein

Z is O or S and is attached to A ;

J is CH and is attached to A , D and J' ;

J' is $C_{1-4}\text{alkyl}$ or phenyl ;

provided that

if $A-D$ is interrupted with $-Z\text{-phenyl-}$, then A is
 $C_{1-5}\text{alkylene}$;

if $A-D$ is not interrupted with $-Z\text{-phenyl-}$, then A is
 $C_{5-12}\text{alkylene}$.

74

27. A compound of Formula (I)

(I)

15 or a pharmaceutically acceptable salt or solvate thereof
wherein

R^1 and R^2 are each H ;

R^3 is $C_{1-3}\text{alkyl}$;

A is $C_{7-10}\text{alkylene}$;

D is $HYC(O)O$;

Y is N and is attached to A ;

G is H , $C_{1-5}\text{alkyl}$, $C_{1-5}\text{haloalkyl}$, $C_{3-7}\text{cycloalkyl}$, phenyl ,
 $-C_{1-2}\text{alkylene-phenyl}$, $C\text{-pyridyl}$ or $N\text{-pyridyl}$, said
 phenyl or $-C_{1-2}\text{alkylene-phenyl}$ are each optionally
and independently substituted with one or more of the
same or different substituents selected from the group
consisting of halo , NO_2 , CN , $-C(O)O-C_{1-3}\text{alkyl}$,
 $C_{1-3}\text{alkyl}$, hydroxy and $C_{1-3}\text{alkoxy}$.

28. A compound of Formula (I)

(I)

or a pharmaceutically acceptable salt or solvate thereof
wherein

R^1 and R^2 are each H ;

R^3 is $C_{1-3}\text{alkyl}$;

A is $C_{1-5}\text{alkylene}$;

D is $HYC(O)O$;

Y is N and is attached to A ;

G is H , $C_{1-5}\text{alkyl}$, $C_{1-5}\text{haloalkyl}$, $C_{3-7}\text{cycloalkyl}$, phenyl ,
 $-C_{1-2}\text{alkylene-phenyl}$, $C\text{-pyridyl}$ or $N\text{-pyridyl}$, said
 phenyl or $-C_{1-2}\text{alkylene-phenyl}$ are each optionally
and independently substituted with one or more of the
same or different substituents selected from the group
consisting of halo , NO_2 , CN , $-C(O)O-C_{1-3}\text{alkyl}$,
 $C_{1-3}\text{alkyl}$, hydroxy and $C_{1-3}\text{alkoxy}$;

wherein $A-D$ is interrupted with $-Z\text{-phenyl-}$;
wherein Z is O or S and is attached to A .

75

29. A compound of Formula (I)

or a pharmaceutically acceptable salt or solvate thereof
wherein

R^1 and R^2 are each independently H;

R^3 is C_1 - C_3 alkyl;

A is C_{7-10} alkylene;

D is $HYC(O)ON=C(G')$;

Y is N and is attached to A;

G is H, C_{1-5} alkyl, C_{1-5} haloalkyl, C_{3-7} cycloalkyl, phenyl, $-C_{1-2}$ alkylene-phenyl, C-pyridyl or N-pyridyl, said phenyl or $-C_{1-2}$ alkylene-phenyl are each optionally and independently substituted with one or more of the same or different substituents selected from the group consisting of halo, NO_2 , CN, $-C(O)O-C_{1-3}$ alkyl, C_{1-3} alkyl, hydroxyl and C_{1-3} alkoxy; and

G' is H, C_{1-5} alkyl or C_{1-5} haloalkyl.

76

30. A compound of Formula (I)

(I)

5

or a pharmaceutically acceptable salt or solvate thereof
wherein

R^1 and R^2 are each H;

R^3 is C_1 - C_3 alkyl;

A is C_{1-5} alkylene;

D is $HYC(O)ON=C(G')$;

Y is N and is attached to A;

G is H, C_{1-5} alkyl, C_{1-5} haloalkyl, C_{3-7} cycloalkyl, phenyl, $-C_{1-2}$ alkylene-phenyl, C-pyridyl or N-pyridyl, said phenyl or $-C_{1-2}$ alkylene-phenyl are each optionally and independently substituted with one or more of the same or different substituents selected from the group consisting of halo, NO_2 , CN, $-C(O)O-C_{1-3}$ alkyl, C_{1-3} alkyl, hydroxyl and C_{1-3} alkoxy;

G' is H, C_{1-5} alkyl or C_{1-5} haloalkyl; and

wherein A-D is interrupted with $-Z-phenyl-$;

wherein Z is O or S and is attached to A.

31. A method of treating chronic pain, acute pain or neuropathic pain in a mammal in need thereof by the administration of an effective amount of a pharmaceutical composition comprising a compound according to claims 21, 22 or 23-30.
